(57) **CLAIM**

The ornamental design for a fishing jig head, as shown and described.

DESCRIPTION

FIG. 1 is a front-top-right perspective view of a fishing jig head showing my new design;

FIG. 2 is a front-top-left perspective view thereof;

FIG. 3 is a rear-bottom-right perspective view thereof;

FIG. 4 is a front elevational view thereof;

FIG. 5 is a rear elevational view thereof;

FIG. 6 is a top plan view thereof;

FIG. 7 is a bottom view thereof;

FIG. 8 is a right-side elevational view thereof; and,

FIG. 9 is a left-side elevational view thereof.

The broken line showing of a hook in FIGS. 1-9 is included for the purpose of showing environmental structure and forms no part of the claimed design.
